WILLIS C. WARD, OF ORCHARD LAKE, MICHIGAN

CARD RACK FOR BRIDGE TABLES

Application filed December 17, 1928. Serial No. 326,613.

The invention relates to card racks, particularly designed for use in connection with the following bridge games which are given over radio. The present invention is in the 5 nature of an improvement upon a prior invention forming the subject matter of Patent No. 1,684,813 issued September 18, 1928. The said invention made use of card holding racks, one for each of the four players, each 10 rack having a series of rows of compartments for receiving the separate cards of a full deck. The cards of the same suit were arranged in the same row and the different suits in successive rows. There were also provided 15 a plurality of decks of cards having the individual cards of each deck visually differentiating from those of other decks on their faces as well as their backs. Thus in use, the cards of the several decks were placed 20 in the racks face downward with the corresponding cards of each deck in the same compartment. When the plays are called, each of the players in succession removes the card called from his rack and places it on the 25 table in the usual manner. Inasmuch, however, as the cards of the several players are clearly differentiated, no confusion can arise as to who has played any particular card which is subsequently found in a trick. 30 After the deal has been played, if the players desire to repeat the play, this may be readily done, as the cards remaining in the racks are arranged in the same manner as those previously played, therefore the deal 35 may be played over as many times as there are decks in the racks and each deal is distinguished from the others by the shade of the cards.

One objection to my previous construction 40 was that the racks when placed on the top of the table, occupied a considerable portion of the area thereof, and to leave any room for the cards to be played, it was necessary to use decks of a diminished size. With my 45 present improvement I can use decks of larger or standard size and at the same time leave the entire top of the table free for the cards which are played. This I have accomplished by a construction of rack which 50 is hung upon the edge portion of the table

and which depends therefrom so as to be in a convenient position for use by the player. A further advantage is that a rack so placed will effectively conceal the cards of each player from all other players. 55

In the drawing:

Figure 1 is a section through a portion of the card table showing my improvement applied thereto:

Figure 2 is a front elevation of the rack as 60 applied to the table.

Figure 3 is a top plan view showing a portion thereof.

As has been stated, my improvement consists essentially of a series of racks A which are engaged with and hung from the edge portions of the table directly in front of each player. Each of these racks A is provided with four rows of compartments with thirteen compartments in each row. Thus a full 70 deck of cards may be held by this rack with the cards thereof arranged in suits and in order. The rack may be formed of any suitable material, but as shown it is constructed of sheet metal having hook portions B which engage with the table top and zigzag portions C which form the successive rows of compartments. The individual compartments in each row may be separated from each other by division strips D and the proportion of 75 parts is such that when the cards are placed in the compartments there will be a sufficient projecting area for reading the cards. I also preferably arrange along the edge of the table and attach to the rack an index 80 of the cards in order as A, K, Q, J, 10, etc. 85

With the construction as described, in use after the table is set up the racks A are hooked on the several sides thereof and the decks of cards, differentiated from each 90 other on face and back as previously described, are distributed in the racks. The cards are first placed with backs up but when the hands are called, each of the players will reverse the cards which are called to 95 him so as to lie face upward in the rack. Subsequently when the plays are called each player removes the card to be played by him from the rack and places it on the table to form the trick, this continuing until the 100

- completion of the plays. Should the players desire to determine their own skill in playing with the same dealt cards, this may be done with the other decks which are in the rack.
- 5 Each player will know the cards which have been previously dealt to him as these are arranged face upward in racks to distinguish them from the remaining cards placed face downward. Thus the play may be repeated a number of times to try out the skill of the various players.

10 The advantages of my present construction over my earlier one are first, that the full area of the table is left unobstructed. Second, that each player can keep in full survey his own cards without being able to see the cards of any other player.

15 It sometimes happens that players wish to preserve a record of certain deals in order that the game may be replayed some time in the future. For such a record I have provided markers which may be used in connection with the compartments in the rack and which will designate the various hands dealt. Thus as shown E are clips which may be engaged with the walls intermediate adjacent rows of compartments and which have heads that are exposed to the front. These clips are preferably in sets of fifty-

20 30 two corresponding to the number of cards in the deck, all of the clips of each set being of a similar color or otherwise identified. Any desired number of sets of such clips may be provided, each set being differentiated from other sets by a different color or shade. Thus whenever it is desired to preserve a record of a hand, clips from one set are engaged adjacent to the compartments of the cards as called and may be allowed

25 35 40 45 to remain as a marker for as long a period as desired. As the clips are quite limited in width, there is space available for the placing of clips from various sets adjacent with the same compartment so that any number of different hands may be recorded in this way.

50 What I claim as my invention is:

1. The combination with a card table, of a rack having means detachably engaging the edge portion of the table for suspending the rack therefrom, said rack being provided with a series of forwardly opening compartments for receiving cards.

55 60 65 70 75 80 85 90 95 2. The combination with a card table, of a rack having a rearwardly opening hook portion adapted to fit over the edge portion of the table for detachably suspending the rack therefrom, said rack being provided with a series of forwardly opening compartments for receiving cards.

In testimony whereof I affix my signature.

WILLIS C. WARD.
